Patented Feb. 15, 1921.

INVENTOR

Ralph C. Simmons
By his attorney,
Nelson M. Howard

UNITED STATES PATENT OFFICE.

RALPH C. SIMMONS, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

DIE.

1,368,363.

Specification of Letters Patent. Patented Feb. 15, 1921.

Application filed November 17, 1917. Serial No. 202,511.

To all whom it may concern:

Be it known that I, RALPH C. SIMMONS, a citizen of the United States, residing at Beverly, in the county of Essex and State of Massachusetts, have invented certain Improvements in Dies, of which the following description, in connection with the accompanying drawings, is a specification, like reference characters on the drawings indicating like parts in the several figures.

This invention relates to dies and especially to cutting dies in which a wall terminates at one extremity in a cutting edge and has at the other a handle by which it may be manipulated and to which operating pressure is applied.

In such dies it may be desired to remove at one time all the pieces of cut material which may have gathered within the wall of the die as a result of successive operations. Such occasion may arise when the cut pieces are to be supplied to the magazine of a machine which operates on them.

An object of the invention is to provide an arrangement of the die and handle whereby access may readily be had to the cut material held in the die. To attain this object I so attach the handle to the die that it may be caused to occupy a position opposite the die opening for the cutting operation, during which said handle approaches or is in contact with the die wall, or a position at one side of the opening to free the die for the removal of the cut material. As illustrated herein, the handle, or a cross bar or member carrying said handle, is pivoted at one side of the die and at the opposite side is separably secured by some such means as a latch.

Another object of the invention is to render the securing means for the die handle constantly associated with the die controllable with a minimum effort and without the necessity for shifting to any marked extent by the operator his grip upon the handle from that existing during the cutting relation to that for the removal of the cut material. To this end I preferably mount the latch upon the handle and so locate the actuating portion thereof that it may be engaged by one finger of the operator without changing the position of the

hand as a whole. The present embodiment of the invention shows the finger piece of the latch extending in the same general direction as the handle but being curved outwardly therefrom to give an effective engaging surface for the operator's little finger.

A further object of the invention is to so arrange the handle that while capable of release as already described, it shall be securely fixed with relation to the die during the cutting operation. Therefore, in addition to the hinged connection, I furnish means for preventing lateral movement of the handle upon the die when they are latched together. This may consist of such engaging means as a projection or projections upon one of the elements entering a depression or depressions in the other.

One of the various possible forms of the invention appears in the accompanying drawing, in which—

Figure 1 is an end elevation of my improved die;

Fig. 2 is a side elevation thereof, parts being broken away; and

Fig. 3 is a perspective view of the die with the handle removed.

At 10 appears the body portion of a die, this consisting of a side wall surrounding an opening of the form of the object to be produced, in the present case the lift of a shoe heel, this wall terminating at its lower portion in a cutting edge 12. Near the upper edge of the die is a lug 14 projecting horizontally and being perforated to receive the pivot which connects the handle portion. The handle proper 16 rises vertically from the center of a cross bar 18, this bar above the lug 14 extending at 20 beyond the die wall and being provided with a pair of depending lugs 22, 22 so spaced from one another as to lie upon opposite sides of the lug 14 and having perforations to receive a pivot bolt 24 which also enters the opening in the lug 14. Between lugs 26 at the opposite end of the cross bar from the portion 20 is pivoted a securing member or latch 28 having a hooked end 30 formed to enter a recess 32 in the wall of the die. To hold the latch projection in engagement with its recess a spring 34 is located between the latch above its pivot and an abutment

36 rising from the cross bar. The finger piece 38 of the latch extends upwardly in the same general direction as the handle 16 but at its extremity is curved outwardly to give an effective engaging surface for the finger of the operator. When the body of the die and the handle are in their normal or cutting relation, they are held against movement over one another laterally by opposite slots or depressions 40, 40 formed in one of the hinged elements, here shown as the die, into which enter projections 42, 42 upon the opposite element. The fit of these depressions and projections is comparatively close so that the two portions when latched together have practically the same rigidity as though they were integral and the hinged connection between them is relieved of all lateral strain.

In using the device, the body portion and cross bar with the handle are latched together and employed in the customary manner until the desired number of cut pieces has accumulated within the die opening or until it is full. Then, without changing the position of the hand upon the handle, the workman may engage the latch portion 38 with his little finger, shifting the latch about its pivot until the projection 30 is withdrawn from the recess in the die body. This allows the cross bar and handle to be swung about its hinged portion, entirely freeing the upper die opening through which the cut material may easily be removed. When the handle and cross bar are swung back to their normal position the rounded edge of the latch rides over the edge of the die wall and the spring 34 seats the projection 30 in its recess to lock the parts together.

Having thus described my invention, what I claim as new and desire to secure by Letters Patent of the United States is:

1. The combination with a die having an opening unobstructed within its wall, of a handle attached to the die at each side of the opening and being movable to occupy either an operating position in which it bridges the die-wall closing the opening against the removal of cut material or a position free of the opening to permit the removal of said material.

2. The combination with a die having an opening, of a handle pivoted to the die to swing either opposite the opening into contact with the edge of the die-wall or to one side thereof.

3. The combination with a die including a wall provided with a cutting edge, of a handle therefor, and a hinged connection between the die and handle permitting said handle to rest normally upon the edge of the wall opposite the cutting edge.

4. The combination with a die, of a handle therefor, a hinged connection between the die and handle, and means independent

of the hinge for securing said die and handle.

5. The combination with a die, of a handle therefor, a hinged connection between the die and handle, and a latch for securing said die and handle.

6. The combination with a die, of a cross bar extending across the die, a handle carried by the cross bar, a hinged connection between one end of the cross bar and the die, and a latch mounted on the opposite end of the cross bar and engaging the die.

7. The combination with a die, of a handle, means for movably connecting the handle and die for constant association, and a retaining member movable with the handle and coöperating with the die.

8. The combination with a die for constant association, of a handle, means for movably connecting the handle and die, and a retaining member movable with the handle and coöperating with the die, said member having a finger piece extending in the same general direction as the handle.

9. The combination with a die for constant association, of a handle, means for movably connecting the handle and die, and a latch movable with the handle and coöperating with the die, said latch having a finger piece extending in the same general direction as the handle and its extremity being curved outwardly from the handle.

10. The combination with a die having an opening, of a handle, means for attaching the handle to the die at each side of the opening, said handle being movable to occupy either an operating position opposite the opening or a position free of the opening to permit the removal of cut material, said handle and die having engaging means to prevent lateral movement of these elements.

11. The combination with a die, of a handle therefor, and a hinged connection between the die and handle, said handle and die being provided with means for relieving the hinge of lateral strain.

12. The combination with a die, of a handle and a hinge for movably attaching the handle to the wall of the die, said handle and die being provided with a coöperating projection and depression.

13. The combination with a die having slots across opposite sides of its wall, a cross bar entering the slots, a handle carried by the cross bar, and means for movably securing the cross bar in engagement with the slots.

14. The combination with a die having an opening, of a handle pivoted to the die to swing either opposite the opening or to one side thereof, the die and handle being provided with a projection and depression which coöperate when the handle is opposite the die opening.

15. The combination with a die having an

opening, of a handle for operating the die mounted thereon to move either opposite the opening into operating engagement with the die wall or to one side of said opening.

5 16. The combination with a die having an opening, of a bar extending across the opening and being pivotally connected at one

extremity to the die, a handle carried by the bar, and a securing device mounted upon the bar at the end opposite the connection to the 10 die.

In testimony whereof I have signed my name to this specification.

RALPH C. SIMMONS.

It is hereby certified that in Letters Patent No. 1,368,363, granted February 15, 1921, upon the application of Ralph C. Simmons, of Beverly, Massachusetts, for an improvement in "Dies," errors appear in the printed specification requiring correction as follows: Page 2, lines 83 and 84 and 90 and 91, claims 8 and 9, strike out the words "for constant association"; same page, lines 85 and 92, claims 8 and 9, after the word "die" insert the words and comma *for constant association*; and that the said Letters Patent should be read with these corrections therein that the same may conform to the record of the case in the Patent Office.

Signed and sealed this 3d day of May, A. D., 1921.

[SEAL.]

T. E. ROBERTSON,

Commissioner of Patents.
